UNITED STATES PATENT OFFICE

ARTHUR RUNKWITZ, OF KIEL-ELMSCHENHAGEN, GERMANY, ASSIGNOR TO FRIED. KRUPP GERMANIAWERFT AKTIENGESELLSCHAFT, OF KIEL-GAARDEN, GERMANY

PULVERIZED FUEL FURNACE

Application filed July 28, 1930, Serial No. 471,288, and in Germany August 9, 1929.

The invention relates to a burner arrangement for pulverized fuel furnaces and has for its object to secure a particularly satisfactory intermixing of the pulverized fuel and the air of combustion. This object is obtained according to the invention primarily by the fact that the main quantity of the fuel and air mixture is fed to the combustion chamber through a plurality of bent 5 pipes arranged in a circle, each bent pipe being surrounded by a wider bent pipe through which additional air is supplied.

In order that the invention can be more readily understood, a preferred embodiment 15 of the same is illustrated by way of example in the accompanying drawings, in which

Figure 1 is a sectional side view of the burner arrangement as applied to the flue of a cylindrical boiler,

Figure 2 shows the burner head, on enlarged scale,

Figure 3 is a front view of the burner head, seen from the right, on the scale of Figure 2, and

Figure 4 is a section along a cylindrical plane as indicated by 4-4 of Figure 3.

The pulverized fuel burner is centrally mounted on a removable furnace front B and comprises an external tubular jacket C 30 closed toward the fire chamber by a burner plate D. Within the jacket C is arranged concentrically a narrow cylindrical tube E and a wider conical tube F. The latter is closed toward the fire chamber by a front plate G through which projects tube E. The burner plate D is connected to the front plate G by bridge pieces or the like and is urged against the front end of the tubes C 35 and F by a cap H by means of a bayonet joint.

The inner tube E serves to supply that portion of the pulverized fuel-air mixture that feeds the ignition flame. This tube E 45 opens toward the fire chamber into a rose-shaped burner which produces only a comparatively short ignition flame, as marked in a dotted line in Figure 2. The main quantity of the pulverized fuel-air mixture 50 is supplied through the annular space exist-

ing between the tubes E and F. Exit of the pulverized fuel-air mixture into the fire chamber takes place through laterally bent pipes K mounted on the front plate G and surrounded by likewise bent wider air 55 pipes L fixed to the burner plate D. The pipes L communicate with the annular space existing between the tubes C and F and serving to supply additional air of combustion. The pipes K and L are arranged 60 in a circle and their mouths, as to be seen from the drawing, have a direction such as to produce a whirl motion in the flue of the boiler.

In the described boiler the entire pulverized fuel-air mixture is decomposed into a plurality of individual jets each of which has allotted to it the required quantity of additional air of combustion which entirely 65 envelops the jet of the mixture, so that a very satisfactory intermixing of the pulverized fuel and the air of combustion is obtained. The centrally arranged ignition burner reliably secures ignition of the main flame. Furthermore, the ignition flame can 70 serve as sole source of heat when the boiler is not in full operation. Finally, the peculiar arrangement of the burner results still in the fact that coarser particles of pulverized fuel that are cast outward by centrifugal force, traverse through the furnace 75 on a longer way along the circumference of the flue and have thus the opportunity to burn out completely.

Owing to the additional air being forced 80 to pass between the front walls D and G of the tubes C and F and to escape through the bent pipes L, the entire burner head both 85 is protected against backward heat radiation from the fire chamber and intensively cooled, and, besides, the additional air of combustion is highly preheated.

What I claim and desire to secure by Letters Patent is:—

1. A pulverized fuel burner comprising a burner plate, a plurality of individual laterally bent burner pipes circularly arranged on this plate, larger pipes each surrounding one of said burner pipes and bent 90 95 100

correspondingly, a tube adapted to supply pulverized fuel-air mixture and communicating with all of said burner pipes, and another tube adapted to supply additional air of combustion and communicating with all of said larger pipes.

2. A pulverized fuel burner comprising a burner plate, a plurality of individual laterally bent burner pipes circularly arranged on this plate, a tube closed on its forward end by said plate and adapted to supply pulverized fuel-air mixture, another plate arranged spacedly in front of said burner plate, pipes corresponding in number to said burner pipes and laterally bent and mounted on said other plate so as to surround said burner pipes, and another tube closed on its forward end by said other plate and adapted to supply additional air to said surrounding pipes.

3. A pulverized fuel burner comprising a burner plate, a plurality of individual laterally bent burner pipes circularly arranged on this plate, a tube closed on its forward end by said plate and adapted to supply pulverized fuel-air mixture, another plate arranged spacedly in front of said burner plate, pipes corresponding in number to said burner pipes and laterally bent and mounted on said other plate so as to surround said burner pipes, another tube closed on its forward end by said other plate and adapted to supply additional air to said surrounding pipes, an ignition burner centrally arranged on said other plate, a third tube arranged within said first-named tube and adapted to supply pulverized fuel-air mixture to said ignition burner.

The foregoing specification signed at
40 Hamburg, Germany, this 12th day of July,
1930.

ARTHUR RUNKWITZ.
